UNITED STATES PATENT OFFICE.

CUMBERLAND M. ROBERT, OF ATHENS, TEXAS.

CHURN.

SPECIFICATION forming part of Letters Patent No. 495,103, dated April 11, 1893.

Application filed November 25, 1892. Serial No. 453,094. (No model.)

To all whom it may concern:

Be it known that I, CUMBERLAND M. ROBERT, a citizen of the United States, residing at Athens, in the county of Henderson and State 5 of Texas, have invented a new and useful Working Body Churn, of which the following is a specification.

The invention relates to improvements in churns.

10 The object of the present invention is to improve the construction of working body churns, to effect a rapid production of butter, and to enable the temperature of the contents of the churn to be readily controlled and regulated to facilitate churning.

15 The invention consists in the construction and novel combination and arrangement of parts hereinafter fully described, illustrated in the accompanying drawings, and pointed 20 out in the claims hereto appended.

25 In the drawings—Figure 1 is a perspective view of a churn constructed in accordance with this invention. Fig. 2 is a central vertical longitudinal sectional view. Fig. 3 is a transverse sectional view.

Like numerals of reference indicate corresponding parts in all the figures of the drawings.

1 The frame 1 designates a frame comprising a base 2 and opposite standards 3 rising from the middle of the base and supported by knees 4 at their lower ends and having journaled between their upper ends a churn body 5. The body is tubular and composed of opposite tapering sections, and is provided at one end with a discharge vent 6 and having on its upper face midway between its ends an opening or mouth 7 which when the churn is in operation is closed by a cover 8. The cover 8 has 5 secured to it a depending tubular tank 9 which is provided with a cover 10, and which is adapted to contain warm water at the commencement and first part of the operation of churning, and cold water when the operation 10 is nearly completed to facilitate and hasten the production of butter. Perforations 11 are arranged at opposite sides of the cover 8 to permit the escape of gases given off during churning. The lower end of the tank is supported by a ring or band 12 which forms a

socket, and which is mounted on a transversely disposed dasher 13. The dasher 13 is provided with perforations and is secured to the bottom and sides of the churn body, and the ring or band which forms the socket for the 55 tank serves to hold the tank stationary with reference to the churn body.

The churn body is provided at each end with a handle and at opposite sides with ears or hangers 15 which receive journals of the 60 standards.

The churn is operated by a treadle 16 arranged at one end of the base, and having its inner end connected with the body by a pitman 17, and having its outer end hinged to a 65 block 18 and provided on its upper face with a cleat 19 to prevent the foot of the operator slipping. The block 18 is removably mounted in a socket at one end of the base; and the socket is formed by a recess 20 of a cross-bar 70 21, and plates secured to the upper and lower faces of the cross-bar. It is of great convenience to have the treadle detachable, to permit it to be removed after the operation of churning is finished, when it might be in the 75 way while removing the contents of the churn body. It will be seen that the churn is simple and comparatively inexpensive in construction, and it is adapted for the rapid production of butter; and I desire it to be understood that changes in the form, proportion and the minor details of construction may be resorted to without departing from the principle or sacrificing any of the advantages of this invention. 85

What I claim is—

1. The combination of a frame, a churn body journaled in the frame and having an opening or mouth, a cover for closing the opening or mouth provided with a depending 90 tubular tank, a transversely disposed dasher, and a band mounted on the dasher and forming a socket and receiving the lower end of the tank, substantially as described.

2. The combination of a frame having standards and provided at one end with a horizontal socket composed of a recessed cross-bar, and plates secured to the upper and lower faces of the cross-bar, a churn body journaled between the standards, a removable block ar- 100

ranged in the socket, a treadle hinged to the block at its outer end, and a pitman connecting the inner end of the treadle with the body, substantially as described.

5 3. The churn body having the dished bottom provided with the rigid dasher 13 at its lowest point, and a socket 12 formed at the top of the dasher, combined with the cover 8 carrying the depending tank 9 also having a

cover 10, and said tank fitting at its lower end 10 in the socket 12, as set forth.

In testimony that I claim the foregoing as my own I have hereto affixed my signature in the presence of two witnesses.

CUMBERLAND M. ROBERT.
